DISMOUNTABLE SHELVING UNITS
Alf J. Bjerke, Braatengaten 24, Moss, Norway
Filed Feb. 21, 1961, Ser. No. 90,736
Claims priority, application Norway Feb. 27, 1960
4 Claims. (Cl. 108—152)

The present invention relates to dismountable shelving units comprising support or columns provided with series of vertical slots in which hooks on shelf-supporting brackets are adapted to engage in detachable association therewith, each bracket comprising means for connecting to a shelf, and on which said shelf rests.

An object of the invention is to provide units of the kind above referred to in which the brackets and shelves may be detachably connected so that the shelves are held against movement in vertical and longitudinal directions with respect to the brackets without the use of separate fastening means, but are limited adjustable longitudinally of said brackets.

The invention is mainly distinguished by a dismountable shelving unit comprising support posts, vertical series of vertical slots along the front sides of said posts shelf-supporting brackets each having on its rear edge a pair of hooks adapted to engage in detachable association with said series of slots, a longitudinal channel-shaped groove at one side of each of the brackets defined by upper and lower side walls, a shelf comprising lower and upper rectangular wire frames interconnected by intermediate cross wires spaced longitudinally of the shelf, the outmost of said cross wires being positioned at a distance from the adjacent ends of the shelf so as to allow the end portions of the wire frames to be moved resiliently towards each other during insertion thereof into the grooves of said brackets, which grooves each has a vertical width smaller than the thickness of the shelf, and means retaining said wire frame ends in said grooves.

The invention will be more fully described by way of example with reference to the accompanying drawing in which:

FIGURE 1 is a perspective view of a shelf unit,
FIGURE 2 is a cross-section along the line A—A in FIGURE 3,

FIGURE 3 is a fragmentary longitudinal section along the line B—B in FIGURE 2, and

FIGURE 4 is a section similar to FIGURE 3, showing the insertion of a shelf end.

In the drawing 1 denotes a flat wire shelf consisting of lower and upper rectangular, elongated wire frames 2 and 3. The central portions of the frames are interconnected by transverse, parallel wires 6, the ends of which are inserted between the longitudinal wire-portions of said frames and secured thereto such as by welding or in another suitable manner. The ends of the transverse wires 6 are crank-shaped or bent downwardly a distance corresponding to the diameter of the wire of the upper frame 3 so that the portions of said wires 6 extending between the side portions of the frames will be level with the upper frame 3, as shown. The transverse wires 6' nearest to the end portions of the frames 2, 3 are positioned at such distance from said end portions, as best shown in FIGURE 3, that the vertically spaced end portions of the frames 2, 3 on the outside of said wires 6' are springy and may be clamped resiliently towards one another.

2

The shelf is supported by brackets 4, which may conveniently be made of sheet metal and are supported by upright support columns or posts 5, preferably of channel shape and each provided along its front side with one or two vertical series of vertical slots 5'.

Each bracket 4 is provided on its rear edge with a pair of attaching hooks 8 adapted to enter a corresponding pair of the vertical slots 5' of the supporting posts 5 for fastening the bracket thereto.

Each of the brackets has a channel-shaped cross-section 7 forming a longitudinal groove 7' at one side of the bracket adapted to receive the end of the shelf 1. The vertical width of said groove 7' is smaller than the thickness of the shelf 1, and the lower side wall of the groove has an upwardly bent portion 11 which serves to retain the lower frame 2 in the groove whereas the upper side wall 12 extends horizontally.

When mounting the end of the shelf 1 the transverse wire at the end of the lower frame thereof is inserted into the lower end of the groove 7' and hooked behind the portion 11 with the bracket in an inclined position as shown in FIGURE 4. When the bracket then is turned about the lower frame wire in the direction of the arrow the upper wall 12 engages the wire of the upper frame 3 and clamps the end portions of the frames 2, 3 towards each other as shown in FIGURE 3.

Connected to the brackets in this manner the shelf 1 is held against movement in vertical and longitudinal directions, as will easily be understood, and may be dismounted in a similar easy manner.

In order that the shelf may be limited displaceable longitudinally of the brackets, the upwardly bent retaining portion 11 at the lower side of the groove 7' is removed at the rear end of the groove, as shown in FIGURE 2, so that the shelf may be displaced outwardly until the lower frame 2 abuts the rear end 11' of said portion 11.

Due to the spring action of the ends of the frames 2, 3 the shelf is held firmly in the groove in set position.

In order that the distance from one shelf to the next above may be regulated within shorter limits than allowed by the fixed distance between the slots 5' the longitudinal central axis *a* of the groove of the bracket is displaced with respect to the middle line *b* between the hooks 8, as shown in FIGURE 2, whereby in changing the brackets at the ends of a shelf the difference in level will be a fraction of the division between the slots 5'.

I claim:

1. A dismountable shelving unit comprising, in combination:
  - (a) two vertically extending support members, each member formed with a row of vertically aligned vertically elongated slots;
  - (b) two horizontally elongated shelf-supporting brackets, each bracket having a pair of hooks releasably engaging two slots in a respective one of said rows and being formed with a longitudinal groove having spaced upper and lower walls;
  - (c) two spacedly superimposed rectangular wire frames; and
  - (d) means for connecting respective central portions of said wire frames, the connected frames constituting a shelf;
  - (e) each frame having two end portions projecting

from the central portion and normally spaced from a corresponding end portion of the other frame in the direction of the thickness of said shelf, the corresponding end portions being resiliently movable toward each other and engaged in the groove of a respective bracket, the spacing of said walls of said groove being smaller than the thickness of said shelf at said end portions.

2. A unit as set forth in claim 1, wherein said walls define therebetween an elongated opening of said groove, and further comprising retaining means on one of said walls and projecting into said opening for retaining one of said end portions in said groove.

3. A dismountable shelving unit as in claim 1, in which said retaining means consist of an inwardly bent portion of one of the side walls of said groove.

5

4. A dismountable shelving unit as in claim 1, in which one of the side walls of said groove has an inwardly bent portion extending from one longitudinal end of said groove and to a point longitudinally spaced from the other end thereof.
